UNITED STATES PATENT OFFICE.

MARION BOAL, OF COSHOCOTON, OHIO, ASSIGNOR OF ONE-THIRD TO WARNER HAY AND ONE-THIRD TO GEORGE M. GRAY, BOTH OF COSHOCOTON, OHIO.

MOLD.

1,095,791.

Specification of Letters Patent.

Patented May 5, 1914.

Application filed May 15, 1912. Serial No. 697,483.

To all whom it may concern:

Be it known that I, MARION BOAL, a citizen of the United States, residing at Coshocton, in the county of Coshocton and State of Ohio, have invented certain new and useful Improvements in Molds, of which the following is a specification.

This invention relates to molds for building up walls from concrete or similar plastic material.

It is the object of the present invention to provide a mold whereby the wall may be built in courses which are divided up into sections in the form of blocks having open spaces at their meeting ends so that the wall is provided with dead air spaces which will resist the passage of heat, cold and moisture.

The invention also has for its object to provide a novel construction of dividing plates and cores, and a novel combination and arrangement of parts to be hereinafter described and claimed.

In order that the invention may be better understood, reference is had to the accompanying drawings forming a part of this specification, in which drawings—

Figure 1 is a plan view of a fragment of the mold. Fig. 2 is a side-elevation thereof. Fig. 3 is a vertical section on the line 3—3 of Fig. 2. Fig. 4 is a perspective view of one of the dividing plates and cores. Fig. 5 is a horizontal section on the line 5—5 of Fig. 4. Fig. 6 is a plan view of a modified form of mold. Fig. 7 is a perspective view of one of the dividing plates and core employed in the last-mentioned mold. Fig. 8 is a perspective view of a stripping board. Fig. 9 is a perspective view, partly broken away, showing another form of mold. Fig. 10 is a perspective view of a dividing plate and core used in the last-mentioned mold. Fig. 11 is a perspective view of one end of the face plate of the mold. Fig. 12 is a perspective view of a stripping board.

Referring specifically to the drawings, the frame of the mold shown in Figs. 1 and 2 consists of longitudinal upper and lower parallel rails 15 and 16, respectively, located in front and at the rear of the mold. These rails carry, on their inner sides, face plates 17 which are spaced apart slightly at their adjacent vertical ends. The face plates are fastened to the rails by bolts 18 which may be secured by wing nuts 19. The length of the rails and the number of face

plates employed will depend on the length of the course or the number of blocks to be molded, and may be varied accordingly. The face plates may have plain, rock or any other kind of faces.

Extending transversely between the face plates, at regular intervals, are dividing plates 20 carrying vertical cores 21, the height of said plates and cores corresponding to the height of the blocks to be molded. The 65 dividing plates extend at their ends into the space between the adjacent vertical ends of the face plates and have lateral bends or hooks 22 which seat in rabbets 23 made in the edge of one of the face plates. By 70 this structure, the dividing plates are securely held in place, and the front and rear frame members of the mold and the face plates carried thereby are held spaced apart a distance corresponding to the thickness 75 of the blocks to be molded. The cores are plates which are secured to the sides of the dividing plates and extend divergently therefrom in opposite directions, their outer ends being connected by a curve. The inner 80 ends of the core plates have inturned flanges 24 which are bolted to the dividing plates. The cores are closed on top by a plate 25 provided with a handle 26. The plates 20 determine the lines of division between the 85 blocks, and as the cores extend from both sides thereof, it will be seen that the blocks are formed with registering dead air spaces in their adjacent ends. The cores are slightly tapered downward to facilitate their 90 withdrawal.

The mold is designed to form the blocks directly on the wall, each block being separated from the other and bonded in the center of the block underneath, as shown 95 in Fig. 2. Any number of mold sections may be employed to make blocks the full length of the wall around the building.

Fig. 2 shows how the mold is supported on the finished portion of the wall. The mold frame fits between front and rear vertical posts 27 located at suitable intervals on the wall, said posts rising from the wall a sufficient distance so that the mold may be set therebetween on top of the last course. The 100 front and rear posts are connected by rods 28 which extend across the top of the last course and pass through the posts and brackets 29 fastened to the outer faces thereof. Wing nuts 30 screwed on the threaded ends 110

of the rods against the brackets secure the rods and hold the posts in place on the wall. The upper ends of the posts are reduced in thickness as shown in Fig. 3 to accommodate 5 the frame member of the mold and bring the face plates flush with the faces of the finished blocks. At 31 is shown by dotted lines in Fig. 1 a stripping board which is placed on top of each mold section when the 10 cores are withdrawn.

Fig. 6 shows a mold in which the blocks are formed in two sections—a front and a rear section, these sections being spaced apart so that the wall is given a continuous 15 dead air space. This result is effected by providing dividing plates 32 similar to the ones already described but having outstanding flat plates 33 secured to opposite sides thereof by angle irons 34. These plates extend 20 in the direction of the length of the block and correspond to the height thereof. The length of the plates is such that their ends meet, so that a continuous air space is made in the wall. The dividing plates are 25 also provided with a suitable handle 35.

Fig. 8 shows a stripping plate employed in the last described mold. It will be noted that this stripping plate has an opening 37 corresponding in outline to that of the dividing plate 32 and the plates 33, so that they may be withdrawn.

In the two forms of mold herein described, the vertical joints will be filled and pointed out after the blocks are finished on 35 the wall. The molds are easy to operate and handle and are simple in construction and can be operated by one man.

Fig. 9 shows a mold for forming the blocks face-down, the blocks not being 40 molded directly on the wall as in the hereinbefore described molds. The frame of this mold comprises longitudinal upper and lower parallel rails 38 to the inside of which are secured, by bolts or other suitable 45 means 39, plates 40 which mold the top and bottom of the blocks. These rails and plates may be the rails and face plates of the molds hereinbefore described, provided, of course, plain face plates are employed. The plates 50 40 are spaced endwise sufficiently to accommodate the ends of the dividing plates and

cores to be presently described. The mold frame is held in set up position by posts 41 located on opposite sides thereof and connected at the top by a cross-beam 42. 55 Set screws 43 are threaded through the posts to bear against the rails 38.

The dividing plates employed in this form of mold are each in two sections, indicated at 44. These two sections are placed 60 between the frame members so as to extend entirely across the mold and form the dividing lines between the blocks. The outer ends of the plate fit in the spaces between the adjacent ends of the plates 40, and have 65 tongues 45 which extend outward between the top and bottom rails 38. In the tongues is a slot 46 through which is driven a wedge 47 said wedge being in contact with the outer face of the plate 40. Each section 44 70 has oppositely extending core-pieces 48 similar to the cores 21, said core-pieces however being positioned in the mold horizontally, as the blocks are molded face-down. The core-pieces 48 of the respective 75 sections 44 meet at their inner ends and their outer ends are tapered inwardly to facilitate their withdrawal from the finished block. The core-pieces of one section may have tenons 49 which seat in mortises 50 in 80 the core-pieces of the other section.

It will be understood, of course, that the frame members of the mold must be spread sufficiently to permit the dividing plates and their core-pieces to be placed therebetween, after which the frame members may be closed up and secured in place by the set-screws 43.

I claim:

A mold having face-plates provided with 90 rabbeted edges, said face-plates being spaced endwise, dividing plates fitting at their ends between the ends of the face-plates and having hook-shaped ends seating in the rabbets, and cores extending from 95 opposite sides of the dividing plates.

In testimony whereof I affix my signature in presence of two witnesses.

MARION BOAL.
